EDWARD H. ELLMS, OF ENGLEWOOD, NEW JERSEY, ASSIGNOR TO THE BARRETT COMPANY, OF NEW YORK, N. Y., A CORPORATION OF NEW JERSEY

DISTILLATION OF TAR

Application filed September 17, 1928. Serial No. 306,330.

This invention relates to improvements in the distillation of tar by utilizing the heat available in the gases produced in coal-carbonization plants, and particularly to the production of clean oil fractions of definite character from such gases. The invention will be described especially with reference to its application to coke ovens.

In the ordinary operation of by-product coke ovens the gases produced by the coking operation pass from the individual ovens through uptake pipes and goose-necks to a collector main common to the ovens of the battery. The "foul" gases leave the ovens at high temperature, e. g., 600° to 700° C. or higher, and carry a considerable proportion of volatilized tars and oils as well as solid particles of coke, coal, carbon and other impurities. Ordinarily the gases are cooled rapidly by the application of sprays of ammonia liquor or ammonia liquor and tar in the goose-necks and collector main, the heat in the gases being thereby dissipated and lost. The rapid cooling causes separation of tar containing the heavier oils in the collector main. Further cooling is effected in the cross-over main and in the condensing system connected therewith and an additional quantity of tar or tarry oil is thus separated. The collected tars and tarry oil are shipped ordinarily from the coke-oven plant to a tar-distillation plant for distillation and separation of the oils and the production of pitches of varying qualities. The expense of handling and of distilling the tar and oil adds to the cost of production of distillation products.

It is the object of the present invention to provide a method and apparatus which permits the distillation of tar at a coke-oven plant, the utilization of the heat of the coke-oven gases for that purpose, and particularly the recovery of definite fractions of clean oils directly by such distillation, together with pitches having the various qualities and characteristics required by the trade.

According to the present invention the heat of the coke-oven gases as they come from the coke ovens is utilized to distill tar and to separate vaporizable oils therefrom by spray-

ing or otherwise bringing the tar into intimate contact with the hot coke-oven gases. The desired distillation can be effected in various types of apparatus as, for example, in a collector main or in uptake-pipe stills as 55 described in the application of George E. Brandon, Serial No. 154,740, filed December 14, 1926, or in any other suitable apparatus in which intimate contact between the hot gases and the tar can be obtained. The 60 intimate contact between the tar and the hot coke-oven gases cools the gases and at the same time the tar is more or less distilled. Partial condensation of the condensable constituents in the gases, more particularly those 65 of a tarry character, results. The scrubbing of the gases with tar tends to separate such tarry constituents. At the same time the gases are enriched with vapors of the more volatile constituents, i. e., oils derived 70 from the distillation of the tar.

The dew points of the gases for the several constituents carried therein as vapor are lower than the normal boiling points of these constituents, and by suitable regulation of 75 the temperature of the gases during the distillation and especially during the subsequent treatment of the gases as hereinafter described it is possible to retain the desired oils in vapor form therein while the tarry constituents are condensed. Thus, by sufficiently lowering the temperature of the gases during distillation in the collector main, for example, all or substantially all of the tarry constituents can be converted into the liquid phase 80 while the desired oils remain as vapors therein. The temperature of the gases should, to accomplish the intended purpose, be maintained above the dew point of the gases for the most readily condensable desired oil constituent or fractions so that substantially all 85 of the oils will be retained as vapor and will be carried over with the gases from the collector main.

Gases leaving the collector main normally 95 contain tarry or pitchy constituents in finely divided form. This finely divided material carried by the gases is known as "tar fog". It is removed from the gases with difficulty and to a greater or less degree persists even 100

in the fuel gases, i. e., the finally purified gases. In the process of my invention, a large portion of this tar fog is removed by the tar which is brought intimately in contact with the hot gases.

5 Some of the tar which is present in the gas stream leaving the ovens may still remain in the gas stream after it has been subjected to intimate contact with the tar introduced for distillation. The quantity of 10 tar fog left in the gas is small and when good contact has been provided between the tar and gases in the distilling operation, it is not usually sufficient to affect the quality of 15 the distillate oil.

15 The entrained tar and "tar fog" can, for example, be separated readily by passing the gases thru an electrical precipitator such, for instance, as the well known Cottrell precipitator, the precipitator being operated at 20 substantially the temperature required to maintain the desired oil constituents in the vapor phase, that is to say, at a temperature higher than the dew point of the gas for 25 the most readily condensable desired oil constituent therein.

30 The electrical precipitator, is, however, not essential to the production of clean distillate oils. A substantial proportion of the entrained tar and "tar fog" in the gases leaving the zone of intimate contact of the gases with the tar to be distilled can be removed by subjecting the gases to a second zone of intimate contact with tar, this second zone of contact 35 being characterized by the fact that the tar is warm and exposed over large surfaces to the gases. Such a condition may, for example, be realized by causing the gases, on leaving the first zone of contact, to pass thru a 40 tower filled with suitable packing over which a current of warm tar is flowing in such quantities that the gases are not cooled below the dew point for the desired oil constituent. It should be noted that the dew point, or 45 more properly the equilibrium point, depends on the material with which the oil vapor bearing gases are in contact and that it is lower when in contact with tar than when in contact with hard pitch.

50 The gases, which have been thus cleaned if desired, will, upon total condensation, yield a mixture of oil constituents. The dew points of the gases for these several constituents are, however, different and in carrying out the 55 present invention advantage is taken of this difference by subjecting the clean gases to cooling in successive stages by indirect heat exchange with liquids boiling at constant temperatures. This heat exchange can be 60 effected in suitable condensers through which the hot gases are passed in heat exchange relation with the selected liquid surrounding, for example, the tubes of the condenser. By selecting a suitable liquid and by venting 65 the space in which the liquid is maintained

to a suitable condenser wherein the vapors produced are condensed and recovered, the temperature to which the clean hot gases are cooled in each such stage may be maintained constant and a fraction of the vapors contained in such gases which condenses at that temperature may be thus recovered. The condensed constant boiling liquid may be returned to its condenser for further cooling of the hot gases.

70 One or more such condensers may be utilized with liquids boiling at different temperatures and the gases may be subjected thereafter to final condensation with a cooling liquid such as water at a temperature 75

80 which ensures the separation of substantially all of the remaining desired vapors from the gases. For example, when making pitch of 400° F. melting point, the clean gases may escape from the electrical precipitator or the 85 second stage tar scrubbing at a temperature of from 240° to 340° C., depending upon the manner of conducting the operation. The gases may be subjected then to cooling in a 90 suitable condenser to a temperature of, for example, 170° to 185° C. by heat exchange 95 with a suitable condensing agent. Such a condensing agent may be a coal tar naphtha fraction having a boiling range of 160 to 175° C. Thereafter the gases may be further 100 cooled to a temperature, for example, of 115° C. by heat exchange with another liquid such as toluol having a boiling point of about 110° C. It will be understood that the liquids 105 selected as condensing agents will depend upon the temperatures which are to be maintained in the respective condensers and that the selection will be made in view of the character of the fractions to be separated 110 from the cleaned coke-oven gases.

115 Thus in the operation as described, the clean gases may be subjected to successive cooling to the indicated temperatures for the purpose of separating first a heavy creosote oil and thereafter a light creosote oil. Further cooling of the gases by heat exchange with a cooling liquid such as water or ammonia liquor, for example, will result in separation of carbolic oil. Thereafter the gases can be conducted thru the usual apparatus for the recovery of ammonia, light oils, etc.

120 When particularly well defined fractions are desired, a fractionating section may be included in the constant boiling liquid condensers. The fractionating section may be composed of plates of the known type or of suitable grids or packing. The fractionating section will be located at the bottom of the condenser in such a way that the condensate from the tubes will run back over the plates or packing and the hot gases entering the condenser will be first forced to pass thru the plates or packing, thereby bringing the condensate and the hot gases into heat ex- 125 130

change relationship and causing rectification of the condensate.

It will be understood that the vapors produced as the result of heat exchange between the hot clean gases and the cooling media will be condensed and recovered and that the liquid so recovered can be returned for further use as cooling media in the condensers. The cooling of the vapors may be effected by heat exchange with a cooling agent circulated thru the condensers for that purpose. The cooling agent may preferably be a liquid which is to be distilled immediately after leaving the condensers. The liquid will be preheated and this will provide a part of the heat which would otherwise have to be supplied in the distilling equipment. A saving in heat is therefore effected. Thus tar may be used as the cooling agent in the condensers; the tar will thereby be preheated and may be partially dehydrated and may then be conducted into the distilling equipment. The heat required to be supplied to the distilling equipment will be less due to the fact that the tar is preheated. The capacity of the gases from a given number of ovens to distill tar is thereby increased. The heat available in such gases is thus utilized effectively for the purpose of the invention and the distillation and recovery of the desired oil products is accomplished economically.

The cooling of the vapors may be effected with a cooling agent other than tar. Thus ammonia liquor may be used as the cooling agent and is thereby preheated and brought into a suitable condition for distillation in the ammonia still. In a like manner, benzolized straw oil or other absorbent oil, may be used as the cooling agent and be thereby preheated and brought into a suitable condition for distillation. If oil fractions are to be redistilled, these oil fractions may be used as the cooling agent and be thereby preheated and prepared for distillation. If the oil fractions are very low boiling, they may even be distilled by means of the heat recovered in the condensers.

The distillation of tar by means of the hot coke-oven gases will be described more particularly with reference to the operation of a collector main although as hereinbefore indicated other apparatus may be adapted for the purpose of the invention. The amount of heat which is available in the gases from all of the ovens of the battery is many times that required to distill all of the tar and oil recovered simultaneously from the battery. Normally, therefore, it will not be necessary to use the gases from all of the ovens unless a quantity of tar is available from other sources or unless tar from the battery has been accumulated. The invention is not limited, however, to the distillation of tar from a single battery of ovens. Tar from other ovens or from other sources such as gas

retorts, vertical retorts and water-gas sets may be distilled in accordance with the invention. It is to be understood, therefore, that provision can be made for utilizing the heat from any desired number of ovens. Usually, 70 however, it is sufficient to employ the gases from only a few of the ovens and these can be connected conveniently to a short collector main or other distillation apparatus in which the distillation is conducted. 75

With such an apparatus, the coke-oven battery and by-product recovery system will not require substantial modification, that is to say, the ovens of the battery may be connected to the usual collector main and a cross-over main may convey the gases from the collector main to the condensing system in which tar and oils are normally separated from the gases. For the purpose of distilling tar a selected number of ovens may be connected, 80 for example, by separate uptake pipes to a short collector main which may be disposed conveniently at the rear of the ovens, suitable valves being provided to permit diversion of the gases from the ovens into the ordinary 85 collector main or into the short collector main so that distillation can be conducted in the latter when desired. 90

The gases in the ordinary collector main may be subjected to cooling in the usual manner with sprays of ammonia liquor or ammonia liquor and tar and the tarry constituents thus separated may be withdrawn for distillation. The gases may be conveyed then to the usual condensers and further cooled 95 therein to separate tarry oil constituents. The tarry oils thus recovered are usually contaminated to a greater or less extent with tar constituents and these tarry oils may be subjected to distillation with the tar recovered from the battery in accordance with the present invention or otherwise treated to 100 separate the constituents thereof. 105

The tar or tar and tarry oil to be distilled may be sprayed into the short collector main thru spray nozzles provided for that purpose and repeatedly recirculated thru spray nozzles, thus ensuring the desired intimate contact of the gases with the tar and/or pitch therein. As a substitute for or adjunct to the spray nozzles agitating devices may be provided in the collector main to thoroughly agitate the tar therein and to throw particles thereof into the gas stream to facilitate the desired intimate contact between the tar and the gases. Thus the nozzles may be entirely replaced by a spray roll or spray discs. Various forms of agitating devices may be utilized for this purpose. 110 115 120

The spraying or atomizing devices should be so arranged that all interior surfaces of the short collector main are liberally flushed with tar or pitch so that any hard pitch which may tend to form therein will be dissolved immediately and absorbed in the stream of 125 130

pitch in the bottom of the main. Pitch is drawn off at one end of the main and tar is added at the other end and at intermediate points if desired at the rate required to maintain the pitch at the desired melting point 5 or the gases leaving the main at the desired temperature. The pitch produced may be withdrawn and utilized as such. By regulation of the temperature of the gases and consequently the extent to which distillation is 10 effected in the distillation apparatus, pitches having the desired qualities and various products having different qualities and characteristics may be made available for commercial use.

15 The gases escaping from the short collector main or other distillation apparatus at the temperature requisite for the recovery of desired oils therefrom following the cleaning 20 of the gases may, if desired, be delivered at such temperature to an electrical precipitator which is disposed preferably closely adjacent to the collector main in order that the temperature of the gases may not be reduced 25 unduly before electrical precipitation of the tar constituents is accomplished. The electrical precipitator employed in the treatment of the gases may be of the type commonly known as the Cottrell precipitator and should 30 be constructed so as to be capable of withstanding the high temperature to which it is subjected in the operation as described. The electrical precipitator may be insulated advantageously to prevent loss of heat from the 35 gases.

The operation of an electrical precipitator 40 as commonly used consists in passing the gas to be treated between electrodes whose difference in electrical potential is very great. Experience has shown that it is best to use a rectified alternating current. The alternating current (the primary) is sent thru a step-up transformer to produce a high potential current (the secondary) which is then rectified 45 to an intermittent uni-directional current, for example, by means of a rotary converter. The rectified current is delivered from the converter to the electrical precipitator at practically the potential at which it 50 leaves the transformer.

The electrical precipitator consists commonly of a group of vertical pipes with a wire or rod in the centre of each, the pipes being connected to proper headers for the 55 introduction and discharge of the gases. The pipes generally constitute the positive electrodes and the wires or rods the negative electrodes. The size of the pipes may vary, but in general pipes of less than six inches in 60 diameter are not used. Electrical precipitators with pipes six inches in diameter using secondary voltages from 35,000 to 50,000 volts are satisfactory for the purposes of this invention. It is generally best to operate 65 with maximum potential difference (second-

ary current) between the electrodes, this maximum being just below the break-down voltage at which arcing occurs.

The efficiency of the cleaning is dependent upon several variables. Satisfactory cleaning of the gas may be accomplished if the time of treatment is of the order of one second, although this time may be varied widely depending upon the character of the oil to be recovered from the gases passing through 70 the precipitator. In working with tubes nine feet long and six inches in diameter, for example, an oil substantially free from all tarry constituents has been obtained with a time of treatment of from one and one-half 75 to two seconds, that is to say, with a gas velocity of from 6 to 4.5 feet per second. This has given an efficiency of cleaning of approximately ninety-nine per cent. If it is desired to collect oils containing small 80 amounts of tar shorter treatment may be used, for example, a treatment of from 0.5 to one second, that is to say, with a velocity of from 18 to 9 feet per second.

From the electrical precipitator the gases 85 carrying the condensable vapors can be conducted directly to the constant temperature condenser or through a series of such condensers. The condenser or condensers may comprise suitable casings enclosing tubes 90 through which the hot gases pass upwardly in heat exchange relation with a surrounding body of the cooling media which as hereinbefore indicated may be selected in view 95 of its boiling point to maintain a constant 100 temperature in the condenser as the result of boiling of the condensing medium at substantially atmospheric pressure. The vapor produced by such boiling may be conducted to another condenser which is vented to the 105 atmosphere and cooled therein to separate the cooling media which may be returned by gravity to the constant temperature condenser. The tar to be distilled may be utilized to cool the vapor and may be heated 110 thus before it enters the short collector main, for example, for distillation therein. If two constant temperature condensers are employed the gases from the first condenser are conducted through the second condenser 115 in heat exchange relation with another liquid boiling preferably at a lower temperature to condense another fraction of the vapors carried by the clean gases. The cooling media will be vaporized and the vapor 120 may be condensed to recover the cooling media by heat exchange with tar, for example. The clean gases still carrying some condensable constituents may be conducted then through a third condenser wherein they are 125 subjected, for example, to direct or indirect cooling by water or ammonia liquor whereby additional constituents are condensed and recovered. The gases can be mingled then if desired with those from the remaining 130

ovens of the battery after such gases have been subjected to cooling and condensation and the mingled gases can be treated for the recovery of ammonia, light oils, etc., in the usual manner.

5 When the heat from the vapor condensers is used to preheat ammonia liquor, or benzolized straw oil, or oils to be distilled, or for other purposes, the tar which is being distilled in the short collector main may be conducted directly to the main without pre-heating or may be preheated in a separate preheater. The liquid which is being pre-heated in the vapor condensers will be conducted thru these condensers countercurrent to the order in which the condensers are arranged with respect to the hot gas flow, so that the entering liquid first cools the vapors from the lowest boiling condenser, and on 10 leaving the series of condensers, the pre-heated liquid will be conducted directly to the equipment where its distillation is to be carried out.

15 The invention is of more or less general application to the distillation of tar to produce pitches and to recover clean oil fractions. It will be further described with reference to the preheating of tar and the cleaning of the gases in an electrical precipitator, 20 as an example, by the following more detailed description taken with the accompanying drawings which show apparatus embodying the invention and adapted for the practice of the process, but it is intended 25 and will be understood that the invention is not limited to the apparatus as illustrated in the drawings, in which

30 Fig. 1 is a plan view of a portion of a coke oven plant illustrating the application of the invention thereto;

35 Fig. 2 is an enlarged sectional view of the short collector main and the electrical precipitator connected thereto; and

40 Fig. 3 is an enlarged sectional view of the constant temperature condensers.

45 Referring to the drawings, 5 indicates the battery of coke ovens in which the individual ovens are connected by uptake pipes and 50 goose-necks 6 to a collector main 7 having a centre box 8 from which the cross-over main 9 conveys the gases and vapors to condensers 10 and 11. The gases may be cooled in the 55 collector main and in the goose-necks leading thereto by ammonia liquor or ammonia liquor and tar introduced through spray nozzles 12 which are supplied through a pipe 13 from a source of ammonia liquor and/or tar such as a storage tank 14. Further cooling 60 is effected in the condensers 10 and 11 and the gases are delivered thence to an exhauster 15 and to the usual equipment (not shown) for the separation of light oils and ammonia from the gases. The tar which separated in the 65 collector main 7 may be withdrawn from the centre box 8 and delivered together with the

tar separated in the cross-over main to a decanter 16 wherein the tar is separated from the ammonia liquor, the latter being delivered to the tank 14. The tar may be delivered to a tank 17 wherein it is stored for distillation 70 in accordance with the present invention. The tarry oils separated in the condensers 10 and 11 may be withdrawn through a pipe 18 to a decanter 19 wherein ammonia liquor is separated from the oil. The tarry oil may 75 be stored then in a tank 20 and can be mingled with the tar to be distilled in desired proportions or treated otherwise for the recovery of constituents thereof.

80 A short collector main 21 may be provided, for example, at the rear of the ovens and may be connected to the desired number of ovens by uptake pipes and goose-necks 22 whereby the hot gases are delivered to the short collector main for utilization therein in the distillation of tar. The tar to be distilled may be delivered through a pipe 23 from the tank 17 to spray nozzles 24 in the short collector main 21 and goose-necks 22, being 85 therein mingled intimately with the hot gases for the purpose of effecting the desired distillation. To facilitate the operation of the short collector main tar or oil or both may be delivered thereto through a pipe 27 so as to flow through the main and flush the bottom thereof. The pitch produced by the distillation may be withdrawn through a pipe 28 for utilization as such or all or any portion thereof may be recirculated through the pump 29 and pipe 30.

90 The gases and vapors resulting from the distillation are withdrawn through a pipe 31 and are delivered to an electrical precipitator which may consist of a shell 33 enclosing a 95 number of tubes 34 which are supported in heads 35 and 36 within the shell. An inlet 37 near the bottom of the shell communicates with a chamber 38 which is partially separated from the tube section by a baffle 39. An outlet 40 permits the escape of gases from the separator after the latter have passed through the tubes.

100 A plurality of electrodes 41, preferably in the form of metal rods weighted at 42, extend through the tubes and are supported from a bus-bar 43 located near the upper ends of the tubes. The bus-bar 43 extends at both ends into casings 44 which enclose insulators 45 upon which the bus-bar is supported. The 105 high tension current line extends into one of the casings and connects with the bus-bar 43, thus supplying the necessary current from any source of uni-directional current under high tension. The casing of the separator is 110 grounded or otherwise connected to the source of current to complete the circuit. The casing and tubes form the positive electrode, the electrodes connected to the bus-bar being negative. The form and arrangement of the 115 conductors in the circuit can be varied. The 120

125

130

arrangement should be such as to supply high tension uni-directional current to the electrodes, thereby permitting a continuous silent discharge between the electrodes and the tubes through which the gases pass.

5 The gases carrying tar in the form of globules or "tar fog", together with solid particles such as carbon, etc. in finely divided form, enter the electrical precipitator and 10 pass through the tubes in the precipitator, being subjected therein to the electrical discharge which through ionization of the solid and liquid particles causes them to separate from the gases and condensable vapors. The 15 separated liquids, together with the solid particles, run down the inner walls of the tubes into the chamber at the bottom of the precipitator and can be withdrawn through a pipe 46, or returned to the short collector main.

20 The gases carrying the condensable vapors escape through the outlet 40 and may be delivered thereby to a condenser 48 comprising a shell with tubes 49 therein thru which the 25 gases pass in heat exchange relation with a body of liquid disposed within the shell. The liquid boils at a constant temperature and the vapor escapes thru a pipe 50 to a condenser 51 which may likewise consist of a 30 shell enclosing tubes 52 thru which the vapors pass. The tubes 52 may be surrounded with a suitable cooling medium such as tar supplied thereto thru a pipe 53. The vapors of the cooling liquid are condensed and returned 35 to the condenser 48 through pipe 50. As shown in the drawings, the tar used in the condenser 51, supplied thru the line 53, may be tar which has been partially preheated, as described below. As shown, the tar es- 40 capes from the condenser 51 thru a pipe 54 which connects with the pipe 23 leading to the short collector main. The tubes 52 communicate with the atmosphere thru an outlet 55 so that the boiling liquid in the con- 45 denser 48 is maintained at substantially at- mospheric pressure so that the condenser operates at a uniform temperature. The liquid which condenses in the condenser 48 is with- drawn thru a pipe 56 to a storage receptacle 50. 57 for the condensate.

The cleaned gases may pass from the condenser 48 thru a pipe 58 to a second condenser 59 comprising a shell and a plurality of tubes 60 thru which the gases pass in heat exchange 55 relation with a surrounding body of liquid boiling at a constant and lower temperature. The vapors thus produced escape through a pipe 61 to a condenser 62 likewise comprising a shell and a plurality of tubes 63 through 60 which the vapors pass in heat exchange rela- 65 tion with a cooling liquid such as tar supplied through a pipe 64 and escaping through a pipe 53. The vapors of the cooling liquid are condensed and returned to the condenser 48 through pipe 61. The tubes 63 of the con-

denser communicate with the atmosphere through an outlet 66 thus maintaining the pressure in the condenser 59 at substantially atmospheric pressure. The liquid condensed in the condenser 59 escapes through a pipe 70 67 to a decanter 68 wherein the oil is separated from any water or ammonia liquor which may be present. The oil is withdrawn through a pipe 69 to a receptacle 70 therefor.

The gases escaping from the condenser 59 75 pass through a pipe 71 to a condenser 72 which may be of the direct or indirect type wherein the gases are subjected to a cooling medium such as water or ammonia liquor from the decanters 68 and 75. The condensate escapes through a pipe 74 to a decanter 75 wherein the oil is separated from the ammonia liquor or water. The oil is delivered through a pipe 76 to a receptacle 77 therefor. The water or ammonia liquor from the decanters 68 and 75 may be delivered through pipes 76' and 77' to a pump 78 and returned thereby through a heat exchanger 79 to the condenser 72 for further use therein. The make of water or ammonia liquor must of course be withdrawn from the system, for example, thru outlet pipe 73.

80 The gases from which the major portion of the condensable constituents have now been removed are withdrawn through a pipe 80 and are delivered to the exhauster 15 which maintains the pressure balance in the system and there mingled with the gases from the remaining ovens of the battery. The 85 gases may be conducted thence through any 90 suitable equipment for the recovery of light oils, ammonia, etc.

The tar used in the condensers may be tar from 17 or tarry oil from 20, or tar or other material may be supplied from any outside 105 source 81. The same cooling medium may be used in both of the condensers 51 and 62 and passed therethru in succession, as shown in the drawings, or a different material may be supplied to each condenser. Where tar is 110 employed as the cooling medium, it may advantageously be run to the short collector main to be distilled therein. The cooling medium need not be run to the short collector main, as shown in the drawings, but may be 115 put to any desired use.

The apparatus as described permits the distillation of tar and the utilization for this purpose of a portion of the heat in the coke-oven gases. It likewise permits the recovery 120 of the oil constituents of the gases in separate fractions having more or less definite characteristics. These fractions may be utilized for any of the purposes to which they are adapted without further treatment 125 or they may be subjected to any desired treatment designed to modify their characteristics and qualities. The invention also permits the production of pitch from the tar recovered from the battery and the character of the 130

- pitch can be varied by modifying the distillation to which the tar is subjected. While such distillation has been described especially with reference to a short collector main, it may be 5 carried out similarly in other types of tar distillation apparatus in which the heat available in coal-distillation gases is utilized to separate vaporizable constituents from the tar.
- 10 Various changes may be made, therefore, in the details of operation and in the apparatus employed therefor without departing from the invention or sacrificing any of the advantages thereof.
- 15 I claim:—
1. The process for obtaining clean oil from tar which comprises distilling the tar by direct contact with hot coal distillation gases, removing entrained impurities from the 20 gases at a temperature above the dew point of condensable oil constituents contained in the gases, cooling the resulting cleaned hot gases and vapors by indirect heat interchange with a body of liquid cooling medium having a relatively constant boiling point within the range of from about 110° C. to about 25 185° C., whereby the cooling medium is kept boiling and the gases and vapors are cooled below the dew point of the condensable oil 30 constituents, and separately collecting the clean oil thus condensed.
  2. The method of distilling tar and recovering distillate therefrom, which comprises distilling coal tar by direct contact with hot 35 coal distillation gases and removing entrained impurities from the gases and then cooling the resulting clean hot gases and vapors by indirect heat interchange with a body of toluol some of which is in the liquid phase 40 and some of which is in the gaseous phase in equilibrium therewith, whereby the toluol is kept boiling and the gases and vapors are cooled below the dew point of condensable oil 45 constituents.
  3. The method of distilling tar and recovering distillate therefrom by heat interchange with a body of cooling medium with a boiling point of approximately 110° C. 50 some of which is in the liquid phase and some of which is in the gaseous phase in equilibrium therewith, which comprises distilling coal tar by direct contact with hot coal distillation gases and removing entrained impurities from the gases, then cooling the 55 resulting clean hot gases and vapors by indirect heat interchange with the cooling medium whereby the cooling medium is kept boiling and the gases and vapors are cooled below the dew point of condensable oil constituents, and then cooling the remaining gases and vapors to separate carbolic oil therefrom.
  4. The method of distilling tar and recovering distillate, which comprises distilling coal tar in a current of inert gases, bringing the 60 resulting gases and vapors into heat 65 interchange with a body of coal tar naphtha having a boiling range of 160–175° C, whereby the naphtha is kept boiling and the gases are cooled to 170–185° C. and heavy creosote oil is separated from the gases and then cooling the resulting gases and vapors by indirect heat interchange with a body of toluol whereby the toluol is kept boiling and the gases are cooled to about 115° C. and light 70 creosote oil is separated from the gases.
  5. The method of cooling a mixture of gases and vapors resulting from the inert gas distillation of tar to condense oils while leaving carbolic oil in vapor form in the gases, which comprises bringing the hot gases and vapors into indirect heat interchange relation with a liquid having substantially the same boiling point as toluol thereby keeping the liquid boiling and condensing oils from 75 admixture with the gases.
- In testimony whereof I affix my signature.
